METHOD FOR PREVENTING REBOILER
SCALINGClarence G. Gerhold, Chicago, Ill., assignor to
Universal Oil Products Company, Chicago, Ill.,
a corporation of Delaware

Application November 16, 1942, Serial No. 465,700

3 Claims. (Cl. 196—75)

This invention relates to a method for preventing reboiler scaling and more particularly to a method of operating reboilers which are employed for heating relatively narrow low boiling range hydrocarbons containing dissolved solids.

The features of my invention make it particularly applicable to isomerization plants in which low boiling hydrocarbons containing dissolved aluminum chloride are heated in reboilers. Difficulty has been experienced in these installations due to the deposition of small quantities of aluminum chloride on the reboiler tubes. This is due to localized total vaporization of the liquid surrounding the tubes because it is necessary that the tube surfaces in order to supply sufficient heat for the process be at temperatures higher than the boiling points of the various components of the liquid. This local vaporization will, of course, cause a deposit of dissolved solids when the liquid evaporates.

In a short time, the deposition of solids on the reboiler tubes will affect the heat transfer coefficient and consequently the efficiency of the system. Aluminum chloride besides decreasing the heat efficiency of the reboiler also has a corrosive effect on many materials especially if any water is present.

By employing my invention, the above mentioned difficulties due to the deposition of aluminum chloride on the reboiler tubes can be eliminated because according to my invention I introduce a higher boiling hydrocarbon, which is substantially inert with respect to the aluminum chloride at the conditions of operation, into the reboiler to retain the aluminum chloride always in solution even in the space adjacent the reboiler tubes.

In order to make the features and advantages of my invention more apparent, reference is made to the accompanying diagrammatic drawing showing one operation to which it may be advantageously applied.

In the drawing, numeral 1 denotes a fractionating column which may be any of the conventional types provided with packing or bubble trays and connected to a suitable reboiler 2 by means of conduits 3 and 4 respectively. Reboiler 2 may be any suitable reboiler in which the heating medium such as steam or hot oil is passed in indirect contact and heat exchange relation with liquid from the bottom of fractionating column 1. The particular reboiler illustrated is provided with a plurality of tubular members 5 through which the heating medium introduced through line 6 and removed through line 7 is passed but any

other type of heat exchange equipment may be employed, for instance, the heating medium may surround the tubes and the liquid to be heated pass therethrough.

5 The bottoms product withdrawn through line 8 from the fractionating column, which in the case wherein this column is used in an isomerization unit for the conversion of normal butane and isobutane, comprises substantially all materials containing four carbon atoms. This material, therefore, will have a relatively narrow boiling range which at atmospheric pressure is in the range of about 9 to 32° F.

The overhead fraction from the column is withdrawn through line 9 and cooled in condenser 10 by means of a cooling medium supplied thereto by means of lines 11 and 12. The cooled and condensed material is conducted by means of line 13 to receiver 14. In receiver 14, the uncondensed 15 gases are separated from the condensate and removed from the system through valve 15 and line 16. The condensate is withdrawn from the receiver by means of line 17 and pump 18 and all or a portion thereof, returned to the top of 20 the column by means of valve 19 and line 20 to act as reflux. A portion of this condensate 25 may be removed from the system by means of valve 21 and line 22. Feed to the column is supplied by means of line 23.

30 In order to retain the dissolved solids always in solution, a higher boiling material which is substantially inert with respect to the aluminum chloride, at the conditions of operation is introduced through line 24 and directed either into 35 the feed to the column by means of line 25 and valve 26 or it may be directed into the feed to the reboiler by means of line 27 and valve 28.

When, for example, fractionating column 1 is the hydrogen chloride column of an isomerization plant, the feed through line 23 will contain 40 a substantial portion of C₄ hydrocarbons together with lighter hydrocarbons and hydrogen chloride plus a small portion of dissolved aluminum chloride. The aluminum chloride will normally remain dissolved at the temperature and pressure conditions of the column, but when this solution comes in contact with tubes 5 in reboiler 2 due to the temperature of the tubes and the relatively narrow low boiling range of the hydrocarbon material, this aluminum chloride would be deposited out as the hydrocarbon vaporizes. When employing my invention, however, that is, introducing a heavier hydrocarbon material such as alkylate or alkylate bottoms from an alkylation plant, the aluminum chloride will always be maintained in

solution and the difficulties due to scaling on the reboiler tubes will be eliminated.

I claim as my invention:

1. A method of preventing scaling on tubes in reboilers during the heating of volatile hydrocarbon liquids containing dissolved aluminum chloride which comprises introducing into said reboiler a higher boiling hydrocarbon liquid which will retain said aluminum chloride in solution and which is inert with respect thereto, and maintaining the last-named liquid at a temperature below the vaporizing point of aluminum chloride.

2. A method of preventing scaling on tubes in reboilers during the heating of low-boiling hydrocarbons containing dissolved aluminum chloride which comprises introducing into said reboiler a

higher boiling relatively inert hydrocarbon liquid which will retain said aluminum chloride in solution, and maintaining the last-named liquid at a temperature below the vaporizing point of aluminum chloride.

3. A method of preventing scaling on tubes in reboilers handling low boiling hydrocarbons containing dissolved aluminum chloride which comprises introducing into the materials to be reboiled a higher boiling hydrocarbon liquid which is relatively inert with respect to and is adapted to retain said aluminum chloride in solution during the reboiling, and maintaining the last-named liquid at a temperature below the vaporizing point of aluminum chloride.
